UNITED STATES PATENT OFFICE.

LEWI LUBIN, OF NEW YORK, N. Y.

WATCHCASE.

1,376,776.

Specification of Letters Patent.

Patented May 3, 1921.

Application filed July 12, 1920. Serial No. 395,480.

To all whom it may concern:

Be it known that I, LEWI LUBIN, a citizen of Poland, and a resident of the city of New York, borough of Manhattan, in the county 5 of New York and State of New York, have invented a new and Improved Watchcase, of which the following is a full, clear, and exact description.

This invention relates to improvements in 10 watch cases, and more particularly to a watch case having an improved construction and arrangement of center or reflector and improved construction and arrangement of back center or movement frame which supports any shape of movement in any shape 15 of frame, the back center or movement frame being correspondingly shaped in accordance with the shape of the movement and the case so as to cover or fill up spaces at the 20 outside of the movement in the case.

A further object is to provide an angular watch case such as is especially adapted for use in connection with wrist watches having 25 an improved construction and arrangement of parts which facilitate the manufacture and assemblage of the watch case and the accommodation of the movement and the result in a watch case which is neat and attractive in appearance, relatively economical to manu- 30 facture, and strong and durable in use.

With these and other objects in view the invention consists in certain novel features of construction, and combinations and arrangements of parts as will be more fully 35 hereinafter described and pointed out in the claims.

In the accompanying drawings—

Figure 1 is a view in front elevation illustrating a watch case embodying my invention.

Fig. 2 is a rear elevation of Fig. 1.

Fig. 3 is a view in rear elevation showing the hinged back or cover of the watch case in open position.

Fig. 4 is an exaggerated view in longitudinal section through the watch case with the movement and crystal removed.

Figs. 5, 6, 7 and 8 are views in elevation or plan illustrating the four principal parts 50 of my improved watch case.

My improved watch case comprises four parts; namely, a case front 1, a front center or reflector 2, a back center or movement frame 3 and a case back 4. In describing 55 these parts, I am employing the terms by

which they are ordinarily known in the trade.

The several parts 1, 2, 3 and 4 are shown of general oblong shape, but it is obvious that the invention is not limited to the precise shape of the case as I may employ any shape desired.

The case front 1 is connected at one end to the case back 4 by means of a hinge 5 at one end of the case, said hinge comprising 65 aligned sleeves 6 and 7 on the case front and back respectively, and a hinge pin 8 positioned in said sleeves. The case front 1 is provided at its ends with strap or bracelet receiving loops 9 which may be of any form 0 desired. The front center or reflector 2 is of the same shape as the case front 1 and fits snugly within the same and is secured therein in any approved manner.

The case front 1 has an opening 10 and 75 the front center or reflector 2 has an opening 11 to expose the watch dial, but the opening 11 in the case front in the center or reflector 2 is slightly smaller in all dimensions than the opening 10 of the case front 80 so as to provide a groove or ledge 13 for the accommodation of the watch crystal 14.

Furthermore, it will be noted that the side portions of the front center or reflector 2 extend beyond the edges of the case 85 front so as to provide flanges or extensions over which the case back 4 snaps or springs tightly into closed position.

The watch movement illustrated by the reference numeral 15 is positioned within 90 the front center or reflector 2 with my improved back center or movement frame 3 located around the movement and having corner plates 16 which fill in the corner spaces around the movement and hold the movement firmly.

It is to be understood that this back center or movement frame 3 will be externally shaped to fit within the front center or reflector 2 and will be internally shaped so as 100 to exactly conform to the shape of the movement and cover all spaces in the watch case at the corners of the movement. For example, as illustrated in Fig. 3, the movement 15 to fit in the watch case such as illustrated is ordinarily provided with beveled corners and the back center or movement frame 3 has the corner plates 16 of the shape and size to fill in the watch case at 105 the corners of the movement, hence, the 110

movement is securely held and the frame covers all spaces and provides a neat and dustproof adjunct to the watch case as will be readily understood.

5 The watch case is provided with an opening 17 for the accommodation of the watch stem 18 and, as above stated, the case may be of various shapes to accommodate movements of various shapes, the frame 3 being 10 of the proper size and shape to compensate for the differences in shape between the case and the movement.

15 Various slight changes might be made in the general form and arrangement of parts described without departing from the invention, and hence I do not limit myself to the precise details set forth, but consider myself at liberty to make such changes and alterations as fairly fall within the spirit 20 and scope of the appended claims.

I claim:

1. A watch case, comprising a case front, a case back movable relative to the case front, a front center or reflector fitting 25 snugly and fixedly within the case front

and forming at the front a crystal receiving ledge and at the back a case back engaging flange, a hinge connecting the case front and the case back, and said case back adapted to snap over the flange of the reflector.

2. The combination with a watch movement of general angular shape having beveled corners, of a watch case, and a movement frame fitting the watch case and having plates at its corners fitting the beveled corners of the movement and covering the spaces formed thereby in the watch case.

3. A watch case, comprising a case front, a case back, a front center or reflector fitting in the case front and having an opening therein slightly smaller than the crystal receiving opening of the case front and extending beyond the rear edge of the case front forming a flange or ledge over which the case back snugly fits, and a back center or movement frame fitting within the reflector and of an internal shape to fit around the movement to be positioned in the case.

LEWI LUBIN.
